UNITED STATES PATENT OFFICE.

IRVING EDWARD SMITH, OF STOCKTON, CALIFORNIA.

OIL-BURNING APPARATUS.

Application filed November 17, 1924. Serial No. 750,248.

This invention relates to improvements in oil burners, and particularly to a type in which oil is fed to the burner and the necessary draft created by means of an electric 5 motor.

The burner apparatus of the present invention includes as essential features therewith, besides the burner structure itself, the motor, and an automatic oil supply device permanently connected together to form a unitary 10 structure. The present apparatus in these respects is essentially the same as shown in my Patent No. 1,512,247 dated October 21st, 1924, on an oil burner, and while retaining all the 15 good features of the previous apparatus, has some important improvements which form the objects of the present invention.

These improvements in the main are:

1. The burner structure adjacent the 20 burner plate has not only been simplified, but this simplified construction positively prevents back-firing, such as was obtained with the previous burner, although I employed means in an attempt to prevent this action.

2. The valve by which the supply of oil to the burner is regulated continuously rotates, and the valve seat is so located that a constant swirl of oil is continuously maintained around the same, thus preventing the valve 25 opening from choking up and insuring a steady and equal flow of oil to the burner at all times.

3. While taking care of any excess or overflow oil in the burner this is not passed to the 30 automatic oil supply device as before, and the need of filtering screens on the burner and in the float controlled supply reservoir is therefore unnecessary. At the same time, I have provided means for enabling any sediment which may be with said excess or overflow oil to be cleaned out of the system even more easily than was the case with the previous structure.

4. A simple and positively acting device 45 has been provided for causing the motor to be stopped in the event that an excessive supply of oil, which is not all being burnt, is being fed to the burner plate, or the float controlled supply device itself floods and overflows.

This stopping of the motor, without the presence of an operator being necessary, prevents possible damage from fire which might occur around the burner if the defective flow of oil were allowed to continue unnoticed, and

also notifies the operator when such conditions obtain so that he may make the necessary investigation and adjustments before again attempting to start the motor.

5. Means has been provided for causing all exterior bearings of the motor shaft and other moving parts to be continuously and automatically lubricated as long as the motor is in operation, the same oil as is used in the burner being employed for this purpose.

These and other objects I accomplish by 65 means of such structure and relative arrangement of parts as will fully appear by a perusal of the following specification and claim.

In the drawings similar characters of reference indicate corresponding parts in the 70 several views:

Fig. 1 is a side elevation of the complete unitary assembly of the apparatus.

Fig. 2 is a sectional view of the burner detached.

Fig. 3 is a sectional view of the float controlled oil supply member shown at approximately the correct level with respect to the burner, as shown in Fig. 2.

Fig. 4 is a top plan view of the burner plate.

Fig. 5 is a fragmentary section of the oil regulating valve stem and its driving connections.

Fig. 6 is a detached view of an automatic motor-circuit controlling member whose action is controlled by an overflow of oil either from the burner or from the float controlled supply member.

Fig. 7 is a sectional view of the oil pump and valve taken on a line 7—7 of Fig. 2.

Referring now more particularly to the characters of reference on the drawings, the numeral 1 denotes a vertical and tubular casing in which is turnably and closely fitted a shaft 2. On the lower end of this shaft is a centrifugal pump runner 3 operating in the usual cylindrical pump cylinder 3^a and adapted to take oil from a passage 4 formed in a bottom cap 5 and to discharge it through the usual tangential discharge outlet 6 of the pump and hence into a passage 7 formed with the casing. This passage leads from the spiral to a circumferential groove 8 provided in the shaft 2 a certain distance above the runner, the shaft being longitudinally bored or orificed as at 9 from this point upwardly, the bore communicating with the groove 8 by means of holes 10. A ball-bearing 2^a sur-

rounds the shaft 2 just above the runner 3 and is arranged to support the shaft. A regulating needle valve 11 projects into a seat 7^a formed at the junction of the passage 7 with the spiral 6 to control the flow of oil from the pump to the shaft. This needle valve 7 never actually closes the seat and projects a certain distance into the spiral 6, as shown in Fig. 2.

Since the runner 3 is constantly rotating adjacent the seat 7^a and setting up a circulation of oil thereabouts, it will be evident that the oil adjacent said seat will never be at rest long enough to cause settling of sediment in the seat to choke up the same, and the projecting valve 11 will be kept clean.

The stem 12 of the valve 11 projects outwardly of the casing through a stuffing box 13 for a suitable distance and is connected to a driving means so as to be continuously rotated as long as the burner is in operation, as will be hereinafter seen. This feature aids in maintaining the passage adjacent the seat 7^a clear and unlogged, as will be evident.

Slidably and turnably mounted on the shaft 2 is the burner plate of an independent unit arranged in driving connection with said shaft, as follows:

A sleeve 14 having a shoulder 15 on its lower end is adapted to fit easily on the upper end 30 of the shaft. Supported by the shoulder 15 and held against rotation on the sleeve is a spiral gear 16, above which is a spacer 17. This spacer supports the inner race and balls 35 of a bearing 18, the outer race of which is permanently seated in the upper end of an opened top cap 19 fixed on the upper end of the casing 1 by suitable means. Resting on the inner race of the bearing 18 is a washer 20 above which is a horizontally disposed fan 21 40 concentrically positioned on the sleeve 14.

Resting on the central portion of the fan and surrounding the sleeve is a spacer 22 on top of which is seated an oil disposing plate 23. The burner plate, fan, inner ball race and 45 the various spacers are all secured to the sleeve 14 to form a rigid unit by means of a tubular nut 24 which screws onto the upper end of the sleeve 14 and fits into the spacer 22 a certain distance, the bore of the latter being 50 enlarged at its upper end to allow this being done. The nut has a shoulder or flange 25 which bears against the plate, thus binding all the parts between this shoulder and the lower shoulder 15 firmly together.

55 This unit structure is held in driving relation with the shaft 2 by means of a transverse pin 26 in the nut which is adapted to seat in a transverse groove 27 cut in the upper end of the shaft 2.

60 The shaft 2 below the groove 27 has a transverse hole 28 communicating with the passage 9, and discharges into the space between the shaft 2 and the nut 24 above the termination 65 of the sleeve 14. The upper end of this nut has a concave taper, as at 29, which serves as a

cup to throw oil outwardly with the rotation of the burner structure.

The above construction enables the burner plate and adjacent parts, which are subjected to the greatest deterioration from heat, to be 70 readily removed for inspection, cleaning or replacement, without having to tear down the entire structure. These parts however are in the main identical with those shown in the patent above referred to, in which this demountable feature is fully covered, and it is therefore unnecessary in the present case to go further into the advantages obtained therewith.

75 The plate 23 is preferably formed as a main substantially flat portion having an outwardly flaring flange 30 projecting upwardly around the rim, which is preferably higher than the nut 24. Openings 31 are provided in suitably spaced relation in the flat or main portion of the plate, these openings being made by cutting slits tangentially disposed relative to the axis of the plate and then pressing the plate down along one edge of the slits and upwardly along the other end of the slits. 80 This causes the air being forced up through the plate from below by the fan to be deflected and to have a centrifugal whirling motion with an upward but angular flow.

85 Meshing with the gear 16, when the above 90 described unit is in position on the shaft 2, is another spiral gear 32 positioned at right angles to said gear 16, the gear 32 being mounted on a shaft 33 journaled in ball bearings mounted both in the casing 1 and cap 19. The 95 direction of rotation of the driving gear 32 is toward the driven gear 16, causing the assembled unit mounted on the shaft 2 to have a downwardly moving tendency, thereby holding the driving pin 26 firmly in the shaft 100 groove 27, as shown in the device in the patent.

105 Fixed on the shaft 2 below the gear 16 is an inverted cone-shaped cup 34, having a hole 110 communicating with the bore 9 of the shaft, so that with the rotation of the latter a small percentage of oil in the bore 9 is thrown into the cup and from there diverted upwardly to spray and lubricate the gears and bearings in the manner fully set forth in the previous patent. The oil preferably used in the burner is 115 "stove oil" which is of a quality to enable it to be used as a lubricant as well as a fuel.

120 Surrounding the casing 1, a certain distance below the top thereof and formed integral therewith is an upwardly sloping dish 125 36 provided adjacent its lowest point with a drain hole 37. A short nipple 38 or the like depends from the drain hole 37 and is adapted to fit freely into the upper end of a drain pipe 130 39 which leads downwardly therefrom to a device hereinafter described.

125 Surrounding the plate 23 and fan 21 is a vertical casing 40 concentric with the shaft and spaced from the outer periphery of said 130

plate and fan a suitable distance. This casing extends from a point somewhat above the plate 23 downwardly to a termination substantially on a level with but inwardly of the upper rim of an inwardly and downwardly tapering oil collecting ring 41. This ring is adapted to discharge into and is supported by the dish 36, the casing 40 being in turn supported on the ring 41 by means of feet 42. The ring 41 also aids in directing the draft of air to the fan and burner plate.

Just below the fan the casing 40 has an inwardly projecting flange 43 which terminates a certain distance inwardly of the outer edges of the fan blades. This arrangement positively prevents a burning mixture above the fan from back-flaring between the fan and casing, as I found was somewhat the case 20 with the previous device.

By means of this structure the air drawn into the fan with the rotation thereof must pass either between the members 36 and 41 or between the latter and the casing 40. In either case the air will have a positive upward travel inside the casing and through the openings in and around the plate 23, thus causing the air to thoroughly mix with the oil being thrown from the member 24 with 30 the centrifugal force set up by the rotation of the parts.

This arrangement of parts and direction of travel of the air keeps the members 36 and 41 cooled down below the igniting point as before, bringing the cool air from the bottom of the burner and furnace around, in and over the dish 36 to the center of the burner first, then up, through, around and over and entirely surrounding the ring 41, being then distributed to all upper parts of the burner. Thus it will be seen that the lower part of the burner is kept cool, preventing any ignition of oil below the casing 40, and preventing any oil from dripping or flowing outside the burner into the bottom of the furnace to cause trouble. This is by reason of the air rushing inwardly between the members and forcing any dripping oil down to the center and into the drain return oil pipe, as herein-after shown.

This burner structure is supported by means of transversely disposed feet 44 which rest on transverse pads 45 mounted at one end of a rigid base member 46 which projects away from the burner a suitable distance so that its outer end is clear of the fire box in which the burner is located.

The shaft 33 is driven by an electric motor 47 supported from the base at its outer end, a suitable rheostat 48 being arranged in connection with the motor to enable the speed thereof to be regulated. The shaft 33 has a bearing 33^a intermediate its ends.

Also mounted on the base adjacent the outer end thereof is an oil supply control device,

comprising a bowl 49 having a float 50 thereon which automatically controls the seating of a needle valve 51 in the oil intake passage 52, so that the oil in the body may be maintained at a definite level as at A, and at the same time 70 the oil pump 3 will be supplied with the necessary amount of fuel. This form of construction being common to various carbureters and the like, as will be evident, no further explanation of the working thereof is thought 75 necessary. The oil is preferably fed to the intake 52 in the manner hereinafter seen.

A pipe 53 is connected to the bowl 49 just above the full level line A and leads thereto from a chamber 54 formed in the burner casing 1 below the dish 34, the bottom of said chamber being at a higher level than the line A in the bowl 49. Thus any oil collecting in the chamber 54 will flow back to the bowl 49 by gravity.

An outlet pipe 55 leads from the bowl 49 near the bottom thereof to the passage 4 of the casing 1, so as to supply the pump 3 with a gravity flow of oil.

A pipe 55^a from a main source of oil supply 90 (not shown) leads to the intake of an ordinary rotary gear pump whose casing is shown at 56. The discharge pipe 56^a from this pump leads to the intake 52 of the bowl 49, with a return pipe 57 beyond said intake leading 95 back to the main tank. Interposed in said return pipe is a pressure relief valve indicated at 57^a, said valve opening away from the intake 52. In this manner oil is fed under a pressure to the bowl 49, whether the main supply tank is below or above the level of the bowl. This type of pump also acts, when not in operation, as an efficient form of valve to prevent any flow of oil through the pipes 55^a and 56^a in either direction. In this manner if the main tank is above the bowl the latter is prevented from flooding, if the needle valve leaks, and conversely if the tank is lower than the bowl the latter cannot drain if the needle valve is defective.

The shaft 58 of the oil pump 56 is driven from the motor shaft 33 by suitable reduction worm gearing 59 preferably enclosed in a casing 60. The shaft 58 drives the valve stem 12 at a reduced speed by work gearing 61 115 also enclosed in a casing 62. Thus the valve 11 continuously rotates in the seat 7^a all the time the motor is running and the burner is in operation.

This valve is adjusted by moving the stem 12 in or out by a straight longitudinal movement rather than by a rotary movement, as is more commonly done. The importance of this construction lies in the fact that neither the needle point 11 or seat 7^a touch each other and as a consequence seat 7^a will always remain the same size and will never be enlarged or forced out of shape. Hence the worm gearing 61^a of said stem, which must remain in a fixed position relative to its worm, is longi- 130

tudinally immovable in the casing 62, while the stem 12 is slidably splined through said gear, as shown at 63 in Fig. 5. Adjusting nuts 64 on the stem 12 outside the casing, 5 with a thrust bearing 64^b in between, regulate the movement of the valve 11 away from its seat, while spring means 64^a on the opposite side of the casing 62 acts to force the valve in the opposite direction or towards its seat. 10 Such adjustment, however, will not have to be made very often, since ordinarily the intensity of the burner fire is controlled by the speed of the motor, and as before stated, the valve 11 is never intended to be entirely 15 closed.

In order to provide force feed lubrication for all worm gears and shaft bearings, a branch pipe 65 leads from the outlet pipe 56^a of the oil pump 56, from which branch pipe 20 leads 66 connect to the various parts to be lubricated, as shown more or less diagrammatically in Fig. 1. Return leads 67 from said lubricated parts connect with the oil return pipe 53 from the burner. In this manner 25 all wearing parts are constantly lubricated by the same oil used for the burner, while any oil not consumed in thus affording lubrication is returned to the bowl 49, since its combustible qualities are not harmed by 30 passing around different bearings.

Automatic shut-down of the motor, should the valve of the bowl become clogged and the bowl flood, or if oil should be excessively discharged into the dish 36 of the burner, is 35 provided for by the following structure:

A small open topped tank 68 is positioned adjacent the base at any suitable point outside the furnace and has a bail 69 removably hung on one end of a horizontal lever 70. 40 This lever is fulcrumed on a bracket 71 which is mounted on the base 46. A weight 72 on the lever counteracts the weight of the tank 68 when the latter is empty; this counteracting weight, after a small amount of oil has 45 flowed into the tank, being added by the weight of a float 73 in the tank and held clear of the bottom thereof, as will be hereinafter seen. This bracket is of such a height that the tank is freely suspended clear of the base. 50 The drain pipe 39 from the burner dish 36 is arranged to discharge into the tank 68 but does not touch the same. This pipe is supported in a removable manner by means of a radial pin 74 depending therefrom intermediate its ends. This pin is loosely socketed in a pedestal 75 mounted on the base. This pin is so positioned relative to the length as a whole that the weight of that portion of the pipe from said pin toward the tank 68 is 55 greater than the portion extending toward the nipple 38, so that the up-turned end of the pipe 39 over said nipple presses upwardly against the dish 36 preventing the lowering of the other end of the pipe 39 beyond a pre- 60 determined point. By means of this arrange- 65

ment, not only is the drain pipe held from undesired contact with the tank 68 but at the same time it may be easily removed when necessary to clear the same of any sediment which may have collected therein.

An overflow pipe 76 leading from the bowl 49 adjacent the upper end thereof is also arranged to discharge into the tank 68 without contacting with the same.

Vertically opposed contacts 77 are arranged in connection with the weight 72, these contacts being normally spaced from but adapted to alternately engage contacts 78 fixed on the bracket 71. In the main circuit leads 79 to the motor 47 is interposed a normally closed switch 80 preferably of the thermostat type. The heating element 81 of this switch is connected by a lead 82 to the corresponding lead 79 ahead of the switch, and has a connection with the contacts 77 through the bracket 71 and lever 70. The contacts 78 are connected in common to the other lead to the motor by means of a lead 83.

The stem 73^a of the float 73 has a yoke 84 straddling the lever 70 on the opposite side of the fulcrum thereof from the bail 69. This yoke has a cross pin 85 below the lever adapted to engage the same only after the float has risen a certain distance. A similar pin 86 is mounted in the yoke above the lever and is normally just clear of the same. The float is normally supported clear of the tank and the pin 86 clear of the lever by means of adjustable nuts 87 on the float stem, which nuts rest on an extension 71^a of the bracket, 90 said extension also forming a guide for the stem. The nuts are preferably adjusted so that the pin 86 is just barely clear of the lever when the tank is empty. Therefore, while the weight 72 alone counterbalances the 95 weight of the empty tank, as soon as any oil flows into the latter and the lever adjacent the pin 86 starts to rise, said pin will take hold and the weight of the float will then aid in counteracting the weight of the tank. 100 In this manner, a larger amount of oil may flow into the tank before the upper contacts 77 and 78 engage each other, as will be evident. After a certain amount of oil has entered the tank, however, either through the 105 pipe 39 or through the pipe 76, the counterbalancing effect of the weight 72 and that of the float will be overcome. This will cause the tank to lower and the thermostat switch heater circuit to be closed at the upper contacts 77 and 78. The heater element 81 of said switch will therefore be heated, causing the switch 80 to be opened and the motor circuit consequently broken. When the tank 110 is disconnected from the lever 70 for cleaning, the removal of its weight from the lever causes the weight 72 to be lowered, so that the lower contacts 77 and 78 become engaged. This of course causes the stoppage of the 115 motor so that the latter cannot be run or the 120

125
130

burner operated until the tank is replaced in position on the lever in an empty condition.

Should any person attempt to frustrate the functioning of the device by blocking up the tank 68 so that it will not lower when oil drains therein, the rising float with the accumulation of oil in the tank will cause the lever to tilt and the upper contacts 77 and 10 78 to be engaged just the same as if the tank itself were lowered and caused this movement of the lever to take place. This is because after the float has risen a certain distance the pin 85 bears against the lever 70 15 causing the latter to move without any movement of the tank itself. When the lever thus moves, while the tank is stationary, the end of said lever adjacent the tank drops away from the bail 69, but since this bail is not 20 permanently affixed to the lever no strain is placed on the lever or bail.

I am aware that overflow tanks, operating knife-switches, have been used for a similar purpose. As far as I am aware however, 25 they only operate in one direction, that is when the tank is lowered with a weight of oil therein. As soon as these tanks are removed, the circuit is restored to unbroken condition. 30 This is contrary to my arrangement, with which breaking of the motor circuit is had when the tank is full, when it is removed, and if the tank should be blocked up and prevented from downward movement. This 35 construction meets the requirements of the

fire underwriters, in providing a device which automatically operates under any and all conditions.

Further, the particular form of motor-circuit control switch enables the switch control circuit to be of low voltage, which allows abutting and sensitive contacts to be used instead of the knife switch which requires more power.

From the foregoing description it will be 45 readily seen that I have produced such a device as substantially fulfills the objects of the invention as set forth herein.

While this specification sets forth in detail the present and preferred construction of the 50 device, still in practice, such deviations from such detail may be resorted to as do not form a departure from the spirit of the invention, as defined by the appended claim.

Having thus described my invention what 55 I claim as new and useful and desire to secure by Letters Patent is:

An oil pump and valve combination for use in pumping heavy hydrocarbon oils, comprising a pump structure having a discharge 60 outlet, said outlet diverging outwardly from the pump, a longitudinally adjustable needle valve pointing toward the pump and constantly disposed in said diverging outlet to form a restricted passage of adjustable cross-sectional area therewith, and means for constantly rotating the valve.

In testimony whereof I affix my signature.

IRA EDWARD SMITH.
